UNITED STATES PATENT OFFICE.

ROBERT S. BOLGER, OF NEW YORK, N. Y., ASSIGNOR TO INTERNATIONAL MOTOR COMPANY, OF NEW YORK, N. Y., A CORPORATION OF DELAWARE.

AERIAL EXTENSION LADDER.

Application filed August 22, 1921. Serial No. 494,130.

To all whom it may concern:

Be it known that I, ROBERT S. BOLGER, a citizen of the United States, residing in the Borough of Manhattan, of the city of New York, in the State of New York, have invented certain new and useful Improvements in Aerial Extension Ladders, of which the following is a specification, reference being had to the accompanying drawings, forming a part hereof.

This invention relates to aerial extension ladders of a type which is very well known, broadly speaking, and has for its principal object to improve such ladders in certain respects, as will appear more particularly hereinafter.

The type of ladder to which the improvements are particularly applicable is one in which spring plungers serve to raise the ladder while pull-down cranks are employed to return the ladder to its bed against the action of the springs. In such ladders mechanism is employed for their traverse and locks are provided to center the ladder with respect to its cradle and to maintain it in any desired predetermined angular relation to the cradle. Further, it is necessary to employ suitable devices to hold the ladder in any desired predetermined angular position with respect to the horizontal and to control its elevating movements under the influence of the elevating springs. The present improvements have to do principally with one or more of the elements enumerated above and seek to bring them into a relationship which is more effective in operation and more convenient for manipulation by a single attendant.

Reference is now to be had to the accompanying drawings for a detailed description of a suitable embodiment of the various improved features, in which drawings—

Figure 1 is a view in side elevation of the improved ladder and controlling mechanism.

Figure 2 is a view in plan thereof, the bed ladder and its supports being removed in the interest of clearness.

Figure 3 is a view in end elevation of so much of the construction as illustrated in Figure 1.

Figure 4 is a fragmentary detail view in section through the turn-table taken on the plane indicated by the line 4-4 of Figure 2.

and looking in the direction of the arrows. 55

Figure 5 is a detail view in vertical section of the controlling worm shaft taken on the plane indicated by the line 5-5 of Figure 2 and looking in the direction of the arrows.

Figure 6 is a view in transverse section through the worm shaft taken on the plane indicated by the line 6-6 of Figure 2 and looking in the direction of the arrows.

Figure 7 is a fragmentary detail view in section on the line 7-7, Fig. 2 of the mechanism for operating the turn-table and the centering lock therefor. 65

Figures 8 and 9 are detail views in horizontal section through the operating shaft for the turn-table showing the improved lock mechanism associated therewith and taken on the planes indicated by the respective lines 8-8 and 9-9 of Figure 1 and looking in the direction of the arrows. 70 75

Figure 10 is a view in side elevation of the hand operated detent for the centering lock.

The bed ladder a is supported pivotally at a^1 on A-frames a^2 secured at opposite sides of a rotatable turntable b on which all the improved mechanism is mounted. The ladder a has extending longitudinally thereof on its upper and lower sides truss rods, c , c^1 which pass around its ends and are interconnected so that bending stresses on the ladder are transmitted throughout the length of such rods. The ladder a has secured thereto at each side a frame d which is connected to the ladder at opposite sides of the pivot a^1 so that in the elevating of the ladder it is subjected to an elevating thrust and an elevating pull. The lower end

of the frame d (and a similar frame at the opposite side of the ladder) is pivotally connected to a pull rod d^1 which is pivoted to a cross head d^2 . The cross head has connected to it spring-pressed plungers d^3 slidable in horizontal cylinders which are mounted fixedly on the turn-table b . The springs d^5 within the cylinders d^4 have their elevating efforts transmitted to the bed ladder by the connections described. The spring-pressed plungers d^3 are held in retracted position by means of a latch D manually operated by means of levers D^1 , D^2 which co-operate with the cross head d^2 . It is necessary, of course, to regulate the speed with which the ladder is elevated under the influence of the

2
springs. This is done by means of a brake band e which cooperates with a brake drum f , secured to a worm shaft f' . Operation of the brake band is effected manually 5 by means of a hand lever e' carried on the turn-table and operatively connected, through the element e^2 , to the brake band. The worm shaft f' is journaled rotatably on the turn-table, but is held against 10 axial movement thereon by means of suitable bearings, one of which is indicated at f^2 . On the worm shaft f' is mounted a nut g , which, when the brake e is released, can travel freely along the worm shaft. The 15 nut g is connected at opposite sides through trunnions g' with pull rods g^2 which are connected to the cross head d^2 . From this description it will be evident that the rate of elevating the ladder under the influence of 20 the springs d^5 may be controlled by the hand brake e which will limit the speed of rotation of the worm shaft f' as the nut g travels along it.

When the bed ladder a is resting in its cradle on the vehicle, the turn-table b will be locked in centered position by means of a plunger lock h which is carried on the turn-table and adapted to enter an opening i in the stationary bed ring i' on 25 which the turn-table is rotatably mounted through balls i^2 and i^4 . The centering lock h is snapped automatically into the opening i , when the turn-table is centered, by means of a spring h' . When the turn-table is to be 30 traversed, however, the centering lock must be withdrawn against the action of the spring h' by means of improved hand-operated devices shown most clearly in Figures 9, and 10. On a stationary part of the turn-table, indicated as a vertical tube k , is pivoted a fork k' . The other end of this element is forked and engages with a collar k^2 carried by the plunger lock h . A bifurcated handle k^2 engages over the outer end of 35 the element k' and is pivoted thereto at k^{10} . The plunger lock h is guided in its vertical movement by a bracket arm k^3 of a supporting column k^4 for the vertical tube k . The bifurcated handle k^2 has 40 formed therewith downwardly extending arms k^5 which ride over shoulders k^6 formed with the bracket k^3 . When the turn-table is locked in its centered position by means of the plunger h , the arms k^5 will rest below 45 the top of the shoulders k^6 , as indicated in Figure 10. When the plunger is to be raised the handle k^2 is elevated about the pivot of the fork k' until the arms k^5 ride over the shoulder k^6 . When in this relation it will 50 be found that the plunger h has been entirely withdrawn from its entering recess i and is locked in elevated position by engagement of the arms k^5 with the shoulder k^6 . This relation will be maintained until the handle 55 k^2 is rocked about its pivot so as to clear the

arms k^5 from the shoulder k^6 . Thereupon the spring h' will become effective to force the plunger h into its recess i .

The mechanism for traversing the turn-table is comparatively simple. The bed ring i' has cut on its inner periphery an internal spur gear i^3 . The turn-table b has journaled therein a vertical rotatable shaft b' on the lower end of which is carried a pinion b^2 meshed with the internal gear i^3 . An operating wheel b^3 is carried at the upper end of the shaft b' . Rotation of the shaft b' with its pinion b^2 will serve to rotate the turn-table to any desired angular position. In order to lock it in any desired 80 predetermined angular position, simple and improved devices are mounted on the vertical column k through which the shaft b' passes. This position lock is made up from a split section of the tube k which is embraced by a split ring k^7 adapted to be compressed by operation of a hand operated nut k^8 threaded on to a bolt k^9 which passes through the free ends of the split nut k^7 . By 85 tightening the hand operated ring k^8 the split nut k^7 will be compressed and bind the tube k on the operating shaft b' so as to prevent further rotation thereof. This locks the turn-table in adjusted angular position.

With the bed ladder a raised it is necessary 95 to depress it either for the purpose of adjusting it against the building or for lowering it to its cradle. Suitable hand operated pull-down mechanism is provided in the improved construction. On the turn-table is 100 journaled a worm shaft l , to the ends of which may be applied hand cranks l' for convenient actuation of the shaft. The worm l^2 , formed preferably adjacent to the mid-section of the shaft l , meshes with 105 a worm gear m on a stub shaft m' which is also supported on the turn-table. The inner end of the stub shaft m' carries one section of any suitable form of clutch, shown in the drawings as a simple dog 110 clutch member m^2 . In proximity to the stub shaft m' is found one end of the worm shaft f' on the end of which is feathered the other member f^3 of a dog clutch which, by means of a hand lever f^4 may be slid into engagement with the dog clutch member m^2 . In 115 this way the worm shaft f' may be connected operatively and at will to the worm shaft l . Rotation of the worm shaft l , when the clutch elements f^3 , m^2 are engaged, will effect rotation of the shaft f' and travel of the nut g in such direction as to pull down the ladder. The irreversible worm connection between the worm l^2 and the worm gear m insures a positive locking of the parts in 120 all positions, against angular movement. Such relation also permits the nicest degree of the adjustment of the angular position of the bed ladder a when in the air. It will be appreciated that with 125 130

- the fulcrum a' of the bed ladder a so near one end, slight movement of the lower end of the ladder is greatly multiplied at the upper end. For this reason, a distinct improvement is realized by providing for a very fine degree of movement through the worm b^2 and worm wheel m . When the ladder is thus nicely adjusted to its proper angular position, it will be held there positively by reason of the interengaging worm b^2 and worm wheel m . When the clutch elements f^3, m^2 are disengaged the worm shaft f' will be free to revolve, subject to the action of the brake band e' thereon.
- From the description given, it will be appreciated that a striking feature of the construction is the central control afforded by all of the elements mounted on the turn-table, each one of these elements being within convenient reach of a single attendant standing thereon. He may, for instance, readily operate the hand wheel b^3 to traverse the turn-table; he may manipulate both the lock devices for centering or for position, through the nut k^8 or the handle k^2 ; he may control the rate of elevating through the brake handle e' and he may throw in the dog clutch f^3 by means of the lever f^4 , whenever the ladder is to be pulled down or locked in predetermined angular position. This organization of parts, by which such convenient central control is placed under the hand of a single attendant, insures quick and effective manipulation of the ladder operating mechanism. Further, the improvements in the component elements entering into this organization are of a substantial and important character in advancing the art.
- What I claim is:
1. In combination with an aerial extension ladder, a turn-table, control mechanism for the ladder mounted on the turn-table and comprising means to traverse the turn-table, means to elevate the ladder, means to lock the turn-table in centered position, means to lock the turn-table in predetermined adjusted angular position, means to control the rate of elevating the ladder, means to lock the ladder in predetermined angular position, and hand operated devices for actuating all of said means mounted on the turn-table within reach of a single attendant.
  2. In an aerial extension ladder, a pull-down nut connected operatively thereto, a worm shaft on which the nut is threaded, a worm wheel an independent worm shaft adapted to be rotated and geared operatively to said worm wheel, and means operatively connecting said worm wheel with the first worm shaft for the purpose of locking the parts against angular movement.
  3. In combination with an aerial extension ladder, means on which the ladder is pivotally mounted and pull-down mechanism for said ladder including a worm and worm wheel in irreversible relation for the purpose of transmitting a pull-down effort to the ladder while locking the parts against relative angular movement.
  4. In combination with an aerial extension ladder, means to support it pivotally, pull-down mechanism including a worm shaft, a nut mounted to travel on the worm of said shaft, means connecting the nut with the ladder in pull-down relation, an independent worm shaft, pull-down cranks for actuating the same, a worm wheel in mesh with the worm on the last named shaft, and a clutch operatively interposed between said worm wheel and the first named worm shaft for operatively connecting and disconnecting the two.
  5. In an aerial extension ladder, means to support it pivotally, power operated devices connected operatively to the ladder for elevating it, a worm shaft, a nut mounted to travel on the shaft, means to connect the nut to the ladder and a brake operatively associated with said worm shaft to control the rate of elevating the ladder.
  6. In an aerial extension ladder, a supporting bed plate therefor, a turn-table mounted rotatably on the bed plate, a spring-pressed position lock carried with the turn-table and adapted to engage the plate to hold the turn-table in centered position, a bracket on the turn-table through which the lock passes and a bifurcated handle engaging the lock and having a toe co-operating with the bracket to hold the lock in released position against the action of its spring.
  7. In an aerial extension ladder, a supporting bed, a turn-table rotatable thereon, a centering lock comprising a vertical plunger carried on the turn-table and adapted to engage the supporting bed and hand operated devices to release the plunger including a pivoted fork, a bifurcated handle pivoted to the fork and engaged with the plunger and a toe carried with the bifurcated handle and co-operating with a fixed shoulder carried with the turn-table.

This specification signed this 16th day of August, A. D. 1921.

ROBERT S. BOLGER.
